PAGE 4

Fig. 4

FIG. 1 is a perspective view of the riding mower, showing my new design;

FIG. 2 is a perspective view taken from the side opposite that shown in FIG. 1;

FIG. 3 is a side elevational view thereof;

FIG. 4 is a front perspective view thereof;

FIG. 5 is a rear perspective view thereof; and

FIG. 6 is a perspective view of a modified form of the riding mower.

I claim:

The ornamental design for a riding mower, substantially as shown and described.
